UNITED STATES PATENT OFFICE.

HARRY W. HARDINGE, OF NEW YORK, N. Y., ASSIGNOR TO HARDINGE CONICAL MILL COMPANY, OF NEW YORK, N. Y., A CORPORATION OF NEW YORK.

APPARATUS FOR DISINTEGRATING ORE AND OTHER MATERIAL.

1,161,859.

Specification of Letters Patent. Patented Nov. 20, 1915.

Application filed December 31, 1908. Serial No. 470,153.

To all whom it may concern:

Be it known that I, Harry W. Hardinge, a citizen of the United States, residing at New York, in the county and State of New York, have invented certain new and useful Improvements in Apparatus for Disintegrating Ore and other Material, of which the following is a full, clear, and exact description.

This invention relates to apparatus for disintegrating ore and other materials, of the conical type described and claimed broadly in my copending application Ser. No. 405,368, patented January 5th, 1909, No. 908,861. In mills of that type the material is disintegrated by agitation in a rotating barrel or drum, preferably aided by a multiplicity of hard balls or pebbles. The barrel is provided with an inlet opening of suitable character, through which the material to be treated is introduced, and with an outlet opening, at the axis of the barrel, through which the ground or disintegrated material is discharged. It is essential that the shape or form of the barrel backward from the outlet opening be conical, and that the said outlet opening be at the apex. Backward from the base of this conical part, which for convenience may be termed the "conical outlet portion" or simply the "outlet portion," the barrel may be variously formed, and, since it contains the inlet opening, may be conveniently termed the "inlet portion." When lumps or pieces of ore or other material, with or without the addition of a multiplicity of hard pebbles, metal balls, or other similar non-friable crushing bodies, are introduced into such a rotating barrel, a new and very striking result is produced; the lumps or pieces of material, and the crushing bodies, if any are used, arrange themselves according to size, the larger in the part of the barrel having the greatest diameter, and from there diminishing in size toward the outlet opening. This arrangement or assortment of the material according to size is preserved during the rotation of the barrel about its longitudinal axis, and as a piece or lump of material is broken up by the impact and attrition of the other masses the pieces promptly move forward toward the outlet opening, where the finest particles escape. It will therefore be seen that the larger pieces, which require heavier impact for their dis-

integration or reduction, are acted on by the larger masses, and when broken are passed on to a point where the masses are smaller and hence where the reducing action is less. In other words, small pieces, which require relatively slight reducing action, are acted on by small masses, and larger pieces by larger masses. In this way the work actually expended upon a piece of any given size is, in general, proportional to the work required for its reduction or disintegration, and there is no energy wasted in subjecting a small particle to the unnecessarily heavy impact and attrition of heavy masses, or large pieces to the ineffective impact and attrition of small masses.

My present invention includes the species illustrated in Figures 5 and 6 of my earlier application before referred to, and also includes novel features of construction not therein shown or described.

In the annexed drawings I have illustrated the mill in its commercial form, arrived at after practical use of the invention for a somewhat extended time; and referring now to the drawings, Fig. 1 is a plan view of the apparatus. Fig. 2 is a side elevation, with the barrel and one of its trunnion bearings in longitudinal section. Fig. 3 is an end view. Figs. 4 and 5 are diagrammatic sectional views of the preferred form of barrel, and a modification thereof, respectively.

The apparatus is conveniently mounted on a foundation 1, provided at its ends with upward extensions 2, 3. On the latter are parallel I-beams 4, 5, supporting transverse bearing members 6, 7.

The barrel 8, mounted in the bearing members in the manner hereinafter described, comprises two trunnion castings 9, 10, with their inner ends conical in form. To the former is secured the conical outlet portion of the barrel, consisting of a cone 11, the pitch of which, or the inclination of its curved surface to its axis, is in the present instance about 30°. To the other trunnion casting, 10, is secured the inlet portion, in the present case a cone 12, of about 60° pitch. Between the cones 11, 12, is a cylindrical portion 13, the length of which, in the mill illustrated, is about one-fourth of its diameter. The whole has a lining 14 of hard brick or other suitable material, and in one side is a manhole provided with a re-

movable closure, 15, for inspection and repair of the lining, introduction and removal of grinding balls, or pebbles, etc. On the trunnion casting 10 is a large gear wheel 16, by which the barrel is rotated, as hereafter described. The trunnion-castings are journaled in bearing bushings 17, 18, each of which is a section of a sphere. These bushings are mounted in correspondingly formed 5 supports 19, 20, on the bearing members 6, 7, so as to be capable of movement in the manner of a ball-and-socket joint. Parallel with the axis of the barrel is a countershaft 21, mounted in ball-and-socket bearings 22, 23, 10 of the same type as those employed with the barrel. At one end of the shaft is a pinion 24, meshing with the gear 16 to drive the same, and at the other end of the shaft is a pulley 25 for connection with a source of 15 power.

From the foregoing it will be evident that either bearing member 6, 7, may be raised or lowered vertically relatively to the other. In such adjustment the spherical bearing 25 bushings of the barrel and the countershaft have a slight movement of rotation about their horizontal diameters, as is shown in the case of the barrel bushings in Fig. 2. At the same time the bearings at the elevated end move axially a slight distance on the journals which they support, to accommodate themselves to the slightly increased distance between them and the corresponding bearings at the other end of the apparatus.

In the machine illustrated the vertical adjustment is effected at the inlet end, by means of vertical adjusting screws 26, 27, working in nuts 28, 29, fixed between the 40 I-beams 4, 5, and extending into contact with the foundation extension 2. When the inlet end has by this means been raised as far as desired, as will be more fully explained hereinafter, suitable blocks 30, equal 45 in height to the space between the I-beams and the foundation, are placed between the same, and the binding bolts 31, the nuts 32 of which are set in recesses in the foundation, are tightened up, thereby clamping the 50 parts firmly together and securing the bearing members 6 in rigid connection with the foundation. The adjusting screws 26, 27, may then be removed, if desired.

The operation of the mill is as follows: 55 The barrel being rotated by power applied to the driving pulley 25, the ore or other material to be disintegrated is fed into barrel through the inlet trunnion 10, with or without a current of water, as may be desired. Inside the barrel the pieces or lumps of ore are subjected to impact and attrition among themselves and the grinding or crushing bodies if such are used. As the lumps of ore are broken up the pieces there- 60 65 of pass toward the outlet, and finally reach

the outlet trunnion 9, where they are discharged. The fineness of the material discharged depends, other things being equal, in general upon the inclination of the barrel with respect to the horizontal. If the axis of the barrel be horizontal the maximum fineness will be produced, and the higher the inlet is raised relatively to the outlet, the coarser will the material be when it reaches the outlet. Soft or very friable material may require the inclination of the barrel to be considerable to reduce the material to the fineness desired but not finer, while harder ore may require the barrel to be practically horizontal in order to obtain the reduction needed. In any case, however, the right inclination for the results desired can be readily ascertained by trial. No more specific directions can be given, since ores and other materials differ so markedly in friability.

As previously stated, the barrel in the preferred form of mill consists of two cones with an intermediate cylindrical portion, as is shown diagrammatically in Fig. 4. The pitch of the outlet cone, 11, may be varied considerably, but in practical use of the invention a cone with a slant of about 30° relative to its axis has been found to give excellent results. The inlet portion, 12, may also be varied, from a cone to a mere plate as shown at 12' in Fig. 5, but its pitch with respect to its axis should be greater than that of the outlet cone. With a 30° outlet cone very satisfactory results have been obtained with a 60° inlet cone. The cylindrical portion 13 affords space for a considerable number of large crushing bodies, and for that reason is desirable, particularly where hard materials are to be reduced. In the mill illustrated the cylindrical part is about one-fourth as long as its diameter, but the length may be varied, being made longer or shorter according as the material on which the mill is to work is harder or softer. In general, however, the cylinder should not be longer than its own diameter, as beyond that size, approximately, even with the hardest ore or other material the power required to revolve the mill, with the large amount of crushing bodies necessary with so large a cylindrical portion, exceeds the gain or advantage which would otherwise flow from having a large cylindrical portion.

The details of construction illustrated in 120 Figs. 1, 2, and 3 may also be varied without departure from the spirit of my invention. However, as before stated, the construction shown in the figures named has been found to give very satisfactory results in practical use.

What I claim is:

1. In an apparatus for disintegrating ore and other material, in combination, a barrel or drum having axial inlet and outlet trun- 125 130

nions, bearing members for the trunnions, each having a cylindrical inner surface surrounding a trunnion and a spherical outer surface, supporting members having spherical inner surfaces to fit the said bearing members, a foundation upon which the supporting members are mounted, means for raising and lowering a supporting member to vary the inclination of the axis of the barrel, and driving means for rotating the barrel, including a driving shaft parallel with the axis of the barrel and supported by said supporting members whereby to remain substantially constant in position relative to the barrel at all positions of the latter.

2. In an apparatus for disintegrating ore and other material, in combination, a barrel or drum, having axial inlet and outlet trunnions, ball-and-socket bearings for said trunnions, separate means for elevating either trunnion independently of the other, and means alongside said drum elevated simultaneously with the elevation of said drum for operating the latter on its trunnions.

3. In an apparatus for disintegrating ore and other material, in combination, a conical barrel or drum having axial inlet and outlet trunnions, ball-and-socket bearings therefor, a shaft alongside of the barrel or drum, ball-and-socket bearings for said shaft, means for raising and lowering the shaft and barrel bearings at one end of the apparatus relatively to the bearings at the

other end, a gear on the barrel or drum, a pinion on the shaft meshing with said gear, and a driving pulley on the shaft, as set forth.

4. In an apparatus for disintegrating ore and other material, in combination, a conical barrel or drum having axial inlet and outlet trunnions, ball-and-socket bearings for the trunnions, means for raising and lowering one of said bearings relatively to the other, a gear on the barrel or drum, a pinion meshing with said gear, and means for rotating the pinion, as set forth.

5. In an apparatus for disintegrating ore and other materials, the combination of a barrel or drum rotatable about its longitudinal axis and having axial inlet and outlet trunnions, a supporting foundation, transverse supports mounted on the foundation at the ends of the barrel, tiltable bearings for the trunnions mounted on the transverse supports, a driving shaft parallel to the axis of the barrel and connected with the barrel to rotate the same, bearings for the driving shaft mounted on said transverse supports and in fixed relation to the said barrel bearings, and means for raising and lowering one of the transverse supports.

In testimony whereof I affix my signature in the presence of two subscribing witnesses. 65
